Primary Examiner — Darlington Ly*Assistant Examiner* — Katherine A Holbrow(74) *Attorney, Agent, or Firm* — Mark V. Leon(57) **CLAIM**

The ornamental design for a display screen or portion thereof with graphical user interface, as shown and described.

DESCRIPTION

The sole FIGURE is a front view of a display screen or portion thereof with graphical user interface showing the claimed design.

The outermost broken line rectangle illustrates a display screen or portion thereof and forms no part of the claimed design. The remaining broken lines illustrate portions of the graphical user interface that form no part of the claimed design.

1 Claim, 1 Drawing Sheet

The image shows a front view of a display screen with a graphical user interface. At the top left is a shield logo. Next to it is a button labeled 'Director'. The main title 'Caliber Club' is centered at the top. Below the title is a section labeled 'Customer Info'. This section contains several input fields: 'Member Code' (with a dropdown arrow), 'Phone' (with a dropdown arrow), 'Email' (with a dropdown arrow), 'First Name' (with a dropdown arrow), 'Last Name' (with a dropdown arrow), and a date input field 'DD/MM/YY' (with a dropdown arrow). To the right of these are four dropdown menus: 'Street 1', 'Street 2', 'Select Country', 'Select State', 'Select City', and 'Zip Code'.
